UNITED STATES PATENT OFFICE.

JOSEPH A. LEVISON, OF NEW YORK, N. Y.

DESIGN FOR A SKIRT-SUPPORTER.

SPECIFICATION forming part of Design No. 28,506, dated April 26, 1898.

Application filed February 16, 1898. Serial No. 670,590. Term of patent 3½ years.

To all whom it may concern:

Be it known that I, JOSEPH A. LEVISON, a citizen of the United States, residing at New York city, New York county, New York, have 5 invented a certain new and useful Design for a Skirt-Supporter, of which the following is a full, clear, and exact description.

My invention relates to a new and original design for a skirt-supporter, shown in the accompanying drawings, in which—

The distinguishing features of my design consist in a body portion of substantially rectangular form, longitudinal and substantially 15 parallel openings in said body portion, and a tongue to the rear of said body portion and substantially parallel therewith and appearing in an approximate median position in respect thereto.
